United States Patent Office.

ZEPHANIAH LOCKWOOD, OF SARATOGA SPRINGS, NEW YORK.

Letters Patent No. 97,660, dated December 7, 1869.

COOKING-STOVE.

The Schedule referred to in these Letters Patent and making part of the same.

To all whom it may concern:

Be it known that I, ZEPHANIAH LOCKWOOD, of Saratoga Springs, in the county of Saratoga, and State of New York, have invented a certain new and useful Cooking-Attachment for Base-Burning Stoves; and I do hereby declare the following to be a full, clear, and exact description of the same, reference being had to the accompanying drawings, making part of this specification, and in which—

Figure 1 is a perspective view of an ordinary "morning glory" base-burning stove with my cooking-attachment thereon;

Figure 2, a similar view with the top plate removed; and

Figure 3, a vertical central section at line xx , fig. 1.

To enable those skilled in the art to make and use the same, I will proceed to describe the same by letters.

A represents an ordinary base-burning stove, over the top of which is fitted the cooking-attachment B, the top of the stove penetrating and being flush with the bottom plate of the cooking-attachment.

To the top plate C is fixed a feeder, D, through which the coal is passed to be burned at the base, the heat and gases rising around and between the outside of this feeder and the stove-cylinder.

On the bottom plate is arranged a circular shield, E, open at the front only, which extends upward, flush against the bottom of the top plate.

A partition, F, extends across from side to side, dividing the space between the plates. A flue is provided in the centre of this partition, and opened or closed by means of a damper, a.

The cooking-attachment extends downward behind the stove, forming the oven G, having double sides, or forming an air-space completely around it, its two ends being provided with doors H. Flues b b are cut through the bottom plate, in front of the partition F, which connect with the air-space or flue, which travels around the oven, and another at the rear end and behind the partition connecting with the same, so that a complete circuit around the oven may be made.

To the front of the cooking-attachment is secured,

on the under side of the bottom plate, a fire-box, I, which is connected, by a flue or flues, with the space between the plates, in order that wood may be burned, and the cooking-attachment used without making fire in the base-burner.

The top plate is provided with the usual openings for cooking-utensils and covers, and a boiler at the rear, and through which the exit-pipe passes.

The operation is as follows:

The fire being lighted, and the feeder filled with coal, the fuel burns at the base, the heat passing up between the feeder and the cylinder into the space surrounded by the circular shield E; from thence it escapes through the opening in the front to the space between the bottom and top plate, heating the same or any utensils on top, and with the damper a closed, it passes down the flues, in front of the partition F, around the oven, up through the rear flue in the bottom plate, underneath the boiler, and out of the exit-pipe J.

When it is desirable to use all the heat against the top plate and boiler, the damper a is opened, so that the draught is such as to prevent the circulation of the heat around the oven.

The rear end of the cooking-attachment is supported by one or more legs, K.

Having described the construction and operation of my improved cooking-attachment,

What I claim as new, and desire to secure by Letters Patent, is—

1. The cooking-attachment B, for base-burning or parlor-stoves, constructed as described, and provided with the feeder-holes for cooking-utensils and boiler, applied and operating substantially in the manner and for the purpose set forth.

2. In combination with the above, the supplemental fire-box I, constructed and operating as and for the purpose set forth.

April 17, 1869.

ZEPHANIAH LOCKWOOD.
